UNITED STATES PATENT OFFICE.

CLARENCE E. VAN DUZER, OF CLEVELAND, OHIO, ASSIGNOR, BY MESNE ASSIGNMENTS, TO THE ADAPTI MANUFACTURING COMPANY, OF CLEVELAND, OHIO, A CORPORATION OF OHIO.

DISTRIBUTING-BOX FOR ELECTRIC CONDUITS.

1,086,630.

Specification of Letters Patent.

Patented Feb. 10, 1914.

Application filed November 1, 1911. Serial No. 657,915.

To all whom it may concern:

Be it known that I, CLARENCE E. VAN DUZER, a citizen of the United States, residing at Cleveland, in the county of Cuyahoga and State of Ohio, have invented a certain new and useful Improvement in Distributing-Boxes for Electric Conduits, of which the following is a full, clear, and exact description, reference being had to the accompanying drawings.

This invention relates to distributing boxes for electric conduits and has for its object the provision of a device of this character made of the smallest possible number of parts and said parts so shaped and designed as to be capable of being interchanged and re-arranged so as to produce boxes of a great many varieties for use under all conceivable situations with the employment of the smallest possible number of separate parts.

Another object is the provision of a device of this character wherein the parts can be assembled into a complete device exactly as they come from the foundry and without the necessity for expensive and laborious machine work.

Other objects of the invention are the provision of a device of this character which shall be susceptible of cheaper production, and more convenient installation than hitherto known devices, and further objects and advantages will be pointed out in the course of the following description and claims.

Generally speaking, my invention may be defined as consisting of the combination of elements recited in the claims annexed hereto, and illustrated in the drawings accompanying and forming a part hereof, wherein:

Figure 1 is a bottom plan view of a distributing box constructed in accordance with my invention; Fig. 2 is a top plan view of the same, the cover being partially removed and certain other parts being still further broken away to illustrate the mode of construction; Fig. 3 is a vertical cross-sectional view taken along the line 3—3 of Fig. 1, the distributing box in this view being illustrated with an attachment for a chandelier; Fig. 4 is a detail cross-sectional view taken along the line 4—4 of Fig. 1; Fig. 5 is a similar view taken along the line 5—5 of Fig. 1, one of the wall sections having been removed; and Fig. 6 a perspec-

tive view of a modified form of wall section illustrating the preferred manner of securing an insulating plate thereto.

Describing the parts by reference characters, 1 indicates the base of my improved distributing box, which is preferably made in the form of a circular cast plate having around its periphery the upturned flange 2. The upper and lower edges of this flange are preferably beveled away as at 2^a and 2^b respectively, the portion between the said beveled edges being left in the form of a perpendicular wall as illustrated at 2^c.

The side wall of the box is made of a plurality of arcuate segmental sections of equal angular extent and of symmetrical formation as regards their meeting edges, whereby they may be arranged in any preferred manner about the periphery of the base member. In the present embodiment I have illustrated four such sections indicated by reference characters 3, 4, 5 and 6 respectively, each section subtending an angle of 90 degrees, although it is obvious that a greater or smaller number of the same could be employed with equal facility. At its lower end, each of said wall sections is formed with a pair of spaced parallel ribs 7 and 8, the inner faces of which are beveled complementarily to the edges 2^a and 2^b respectively. The adjacent ends of the sections are formed at the space between said ribs with semi-circular notches 9—9, and the flange 2 is formed with spaced threaded apertures 10 adapted for the reception of screws 11 whereby said sections may be clamped rigidly about said base member.

In order that the setting up of these screws may tighten the joints between the adjacent wall sections in a workmanlike manner, I preferably form the ends of said sections upon a bevel as shown at 15, the inclination of said bevels being progressive about the box whereby the sections may be assembled in any desired relation.

It will be obvious from the foregoing that, since the screws 11 are secured at equal intervals around the base 1, and since the sections 3, 4, 5 and 6 are of equal angular extent and symmetrical form, they can be arranged in any preferred order, and when so arranged can be drawn into tight and firm relation with each other by merely setting up said screws. Certain of these wall members will be formed with hollow bosses 3^a 110

and 5^a which can be suitably threaded or otherwise adapted for the reception of conduits 16 and 17 as illustrated, and said bosses can be of the same or different sizes as convenient. Other sections as 4 can be provided with insulating bushings for the passage of electric wires, while other sections like 6 can be left bare. In the case of sections which, like sections 3 and 5, are provided with bosses, the face of one of the bevels 15 is preferably substantially parallel with the axis of that boss so that the sections can be cast readily, the parting line of the casting coinciding with the outer surface of the section. The other bevel will make an angle with the first bevel equal to the angle subtended by the whole segment, in this instance 90 degrees, and the parting line will obviously fall upon this surface (see 15^a). 15

20 It will therefore be apparent that a box made in accordance with my invention can be cast in finished form and assembled with a minimum of machine work, since the parting line of the casting will coincide with the outer 25 surface of the section. The upper or free edges of the wall segments are formed at similar points with lugs or ears 20, the same being preferably apertured for the reception of screws 21 whereby the cover 22 may be 30 secured in place, and the symmetrical arrangement of these lugs will permit the application of the cover irrespective of the arrangement of the wall sections.

In Fig. 3 I have illustrated a box, the 35 bottom 1^a of which is provided with a threaded axial boss 25 adapted for the reception of an electrolier or other pendant, the cover being omitted in accordance with the usual practice in such cases. The height 40 of the flange 2 is preferably decreased somewhat intermediate the screw holes 10 in order that the passage through the bosses 3^a and 5^a be not impeded thereby, and this portion of the box is preferably rounded off as shown 45 at 26 in Fig. 3.

In Fig. 6 I have illustrated the preferred method of securing an insulating plate to a wall section when it is desired to lead separate wires from the conduit to a fixture or 50 motor adjacent thereto, and especially in case three phase current be employed. In this view I have shown the section as provided with an oblong window opening 30 having about its inner portion a ledge 31. 55 A curved plate 32 of porcelain, fiber, vulcanite, or other suitable material is inset in this window and secured therein by screws 33 threaded into the section and having their heads overlapping the edges of the plate. 60 This plate can be perforated for any convenient number of wires as will be obvious.

It will be understood that I have employed the expressions "top", "bottom", "upper", "lower", etc. in their ordinarily accepted 65 meanings and not as relating to the position

of the box when installed. When the box is used as a ceiling outlet as shown in Fig. 3, it is installed in the inverted position shown, but its use is not restricted to this position, as will be well understood by those skilled in the art. 70

While I have necessarily described my invention in detail, I do not propose to be limited to such details, except as the same may be positively included in the claims hereto 75 annexed, or may be rendered necessary by the prior state of the art.

I claim:

1. A distributing box for electric conduits, comprising, in combination, a circular plate 80 having radial threaded apertures spaced at equal distances therearound, segmental wall sections adapted to fit around said plate and to subtend the angle between adjacent apertures, the ends of said sections being formed 85 with notches adapted to register with said apertures and to coöperate with the similar notches of adjacent sections in forming screw-receiving apertures, and screws received in said apertures and having heads 90 bearing against the adjacent outer walls of said sections whereby said sections are secured together and to said circular plate.

2. A distributing box for electric conduits, comprising, in combination, a metallic plate 95 having threaded apertures in its edge, segmental wall sections adapted to fit together so as to surround said plate, the length of each section being such as to cause it to extend from the middle of one aperture to the 100 middle of another aperture, the ends of said sections being formed with notches adapted to register with said apertures and to coöperate with the similar notches of adjacent sections in forming screw-receiving apertures, and screws received in said apertures and having heads bearing against the outer walls of said sections whereby said segments are clamped against the edge of said plate. 105

3. A distributing box for electric conduits, comprising, in combination, a substantially circular metallic plate having the sides of its edge beveled in opposite directions, a plurality of segmental wall sections adapted to surround said plate, each of said wall sections having adjacent one edge a pair of spaced parallel ribs, the adjacent faces of said ribs being inclined complementarily to the beveled edges of said plate, and radial screws threaded into said plate and engaging said wall sections whereby the latter are held in position. 115

4. A distributing box for electric conduits, comprising, in combination, a flat metallic plate having its edge beveled, a plurality of segmental wall sections adapted to surround said plate, each of said wall sections having adjacent one edge a seat shaped complementarily to the edge of said plate, and radial screws threaded into said plate between ad- 125 130

adjacent wall sections and having their heads overlapping said sections, said sections being notched to permit the passage of said screws.

5. A distributing box for electric conduits, comprising, in combination, a substantially circular metallic plate having the sides of its edge beveled in opposite directions, a plurality of segmental wall sections adapted to surround said plate, each of said wall sections having adjacent one edge a pair of spaced parallel ribs, and the ends of said sections between said ribs, being formed with notches and screws secured to said plate and passing through said notches, the heads of said screws overlapping adjacent edges of said wall sections whereby the latter are secured to said plate.

6. A distributing box for electric conduits, comprising, in combination, a metallic plate having a peripheral upturned flange, the top and bottom of said flange being oppositely beveled and said flange being formed with spaced radial screw-receiving apertures, a plurality of segmental wall sections adapted to surround said plate, the length of such sections being such as to subtend the angle between the centers of adjacent apertures, and said sections having notches at their ends adapted to register with said apertures, the inner sides of such sections being formed with grooved portions corresponding in shape to the exterior of said flange, screws in said apertures and having heads overlapping the exteriors of said sections, apertured lugs formed at the opposite edges of said sections, and a cover member secured to said lugs.

7. A distributing box for electric conduits, comprising, in combination, a metallic plate having a peripheral upturned flange, formed with spaced radial screw-receiving apertures, a plurality of segmental wall sections adapted to surround said plate, the length of such sections being such as to subtend the angle between the centers of adjacent apertures, and said sections having notches at their ends adapted to register with said apertures, the inner sides of such sections being formed with grooved portions corresponding in shape to the exterior of said flange, certain of said sections being formed with external,

conduit receiving bosses, and said flange being partly cut away between adjacent screw receiving apertures so as not to obstruct said conduits, screws in said apertures and having heads overlapping the exteriors of said sections, apertured lugs formed at the opposite side edges of said sections, and a cover member secured to said lugs.

8. A distributing box for electric conduits, comprising, in combination, a metallic plate having radial spaced apertures therein, a plurality of segmental wall sections adapted to surround said plate, the length of each of said sections being substantially equal to the distance between the centers of said apertures, the ends of said sections being beveled so as to overlap each other and the angle of such bevels being progressive about said plate, and screws secured in said apertures and having heads overlapping the outer surfaces of said sections whereby the latter are secured to said plate.

9. A distributing box for electric conduits, comprising, in combination, a metallic plate having radial spaced apertures therein, a plurality of segmental wall sections adapted to surround said plate, the length of each of said sections being substantially equal to the distance between the centers of said apertures, certain of said sections being formed with radial bosses, the meeting ends of said sections being beveled whereby said sections may overlap each other, the angle of such bevel at one side of said boss being not less than sufficient to render said end parallel with the adjacent side of said boss, and the surface of the opposite end of said section making an angle with said first end substantially equal to the whole angle subtended by said section, and screws secured in said apertures and having heads overlapping the outer surfaces of said sections whereby said sections are secured to said plate.

In testimony whereof, I hereunto affix my signature in the presence of two witnesses.

CLARENCE E. VAN DUZER.
